UNITED STATES PATENT OFFICE.

IVERT LARSEN, OF CHICAGO, ILLINOIS, ASSIGNOR, BY MESNE ASSIGNMENTS, TO THE AUTOMATIC RECORDING SAFE COMPANY, OF CHICAGO, ILLINOIS, A CORPORATION OF ILLINOIS.

SAVINGS-BANK.

1,150,525.

Specification of Letters Patent. Patented Aug. 17, 1915.

Application filed February 6, 1911. Serial No. 606,907.

To all whom it may concern:

Be it known that I, IVERT LARSEN, a citizen of the United States, residing at Chicago, in the county of Cook and State of Illinois, have invented a new and useful Improvement in Savings-Banks, of which the following is a specification.

My invention relates particularly to savings banks commercially known as of the recording type; and my primary object is to provide a bank of this character having improved features of construction and operating in an improved manner.

My improved savings bank is preferably constructed largely from sheet metal, and is equipped with an improved locking means and also with improved coin-slot guards.

Further details of improvement pertain to the construction of certain metal parts employed.

The invention is illustrated in its preferred embodiment in the accompanying drawings, in which—

Figure 1 represents a perspective view of a savings bank constructed in accordance with my invention; Fig. 2, a horizontal section taken as indicated at line 2 of Fig. 4; Fig. 3, a horizontal section taken as indicated at line 3 of Fig. 4; Fig. 4, a vertical sectional view of the savings bank taken as indicated at line 4 of Fig. 3; Fig. 5, an enlarged broken vertical sectional view showing details of the lock employed; Fig. 6, a broken elevational view of the key employed; Fig. 7, a broken elevational view of the post-form locking member with which the removable core of the savings bank in which the money chambers are formed is equipped; Fig. 8, a plan view of a tumbler or guard employed in connection with the lock; Fig. 9, a perspective view of the rotary tubular locking member; Fig. 10, a plan view of the same, showing also the spring employed in connection with said rotary locking member; Fig. 11, a section taken as indicated at line 11 of Fig. 5, but showing the post-carried locking member in dotted lines; Fig. 12, a view similar to Fig. 11, but showing the rotary locking member rotated against the tension of its spring to the releasing position; Fig. 13, an enlarged broken sectional view showing a detail of one of the coin-slot guards; Fig. 14, a sectional view taken as indicated at line 14 of Fig. 13; Fig. 15, a broken lower side view of the

guard-carrying plate, detached from the upper wall of the casing or shell by which it is carried; Fig. 16, a perspective view of one of the guide-cylinders carried by the plate mentioned; and Fig. 17, a perspective view of one of the plungers, or coin-slot guards.

In the construction illustrated, A represents a core, or body, equipped with a plurality of coin-chambers and having its base provided centrally with a post A' whose upper end is formed to provide a locking member; and B, a casing or shell adapted to receive the core, or body, A, said shell having its top wall equipped with a depending locking device B' which coacts with the post-form locking member A'.

The body, or core, A comprises a base 1 which preferably is of circular form and may be stamped from sheet metal; and a series of coin-chambers 2 which rise from the base at or near the periphery thereof, being arranged substantially in the form of annulus. The chambers, or coin-receptacles, 2 are of partially cylindrical form, having curved part-cylindrical walls 3 at their inner sides and openings, or slots, 4 at their outer sides. The walls 3 of each receptacle 2 extend preferably approximately through two-thirds of a circumference, so that the coins will be sufficiently embraced to prevent them from falling from the receptacles when the shell is removed. Each receptacle 2 may be formed from sheet metal, and may have a bottom member 5 formed by a suitably shaped extension of the metal which is bent at right angles to the wall 3, so as to have its edges embraced by the lower marginal portions of the wall 3, the metal being left unsevered, as indicated at 6. The receptacles thus formed are secured to the sheet metal base, as by means of rivets 7. The receptacles 2 are of sufficient height to extend near to the top of the casing or shell, but are cut away at their upper portions to accommodate the coin-slot guards and to admit coins which may be inserted through the coin-slots with which the shell is provided in its circumferential wall at the upper end portion thereof. The post A' may be riveted to the central portion of the base 1, as indicated at 8. Said post A' is formed at its upper end with a locking-member 9 (Fig. 7). This locking-member is formed by reducing the upper end portion of the post, as indicated at 10, and providing the

extremity of the reduced portion with a transverse elongated head 11 having oppositely disposed projections 12 whose lower surfaces afford locking-shoulders. As thus described, the head 12 is of substantially oval form and rounded or beveled on its upper side to facilitate engagement with the locking device carried by the shell.

The coin-receptacles 2, which are of different sizes to accommodate coins of different denominations, encircle or surround a chamber 13 adapted to receive bills.

The shell, or casing, B comprises a top 14 and a depending circumferential wall, or flange, 15. The wall 15 is adapted to encircle the coin-receptacles, thus closing the vertical slots or cut-away portions 4 of the coin-receptacles. The cup, or shell, thus described may be formed from sheet metal by a series of stamping operations. The circumferential wall 15 is provided near its upper end with a series of coin-slots 16 corresponding in size with the coin-receptacles with which they correspond. The shell is further provided with a bill-opening 17 leading to the central bill-chamber 13. As shown, the opening 17 is in the top of the shell or casing. Secured to the under side of the top 14 of the shell, as by means of rivets 18, is a sheet metal spider or plate 19 of annular formation and adapted to carry a series of guide-cylinders 20 fitted with plungers, or coin-slot guards, 21. The guard-carrying plate 19 has the portion adjacent its central opening struck up, as indicated at 22 in Fig. 5, to facilitate connection with the top wall of the shell. The body of the plate inclines downwardly and outwardly, and at its periphery is equipped with upturned spacing-lugs 23 whose upper ends abut against the inner surface of the casing-top, as will be understood from Figs. 2 and 13. The plate 19 is provided near its upper portion with a series of rectangular perforations 24 adapted to receive the guide-cylinders 20. The guide-cylinders 20 are provided at their inner ends with slots 25 adapted to engage the inner walls 26 of the openings 24. Each plunger 21 is provided on opposite sides with slots 27 adapted to engage the edge walls 28 of slots 29 which open from the outer ends of the slots 24 to the periphery of the plate 19, as shown in Fig. 15. Each guide 20 contains a spring 30 adapted to project the plunger 21, as shown in Fig. 14. It will be noted from Fig. 13 that the slot-guarding plungers incline downwardly and outwardly and have their outer ends impinging against the inner cylindrical wall of the casing, so that the plunger can be retracted by the insertion of a coin.

The locking-device B' carried by the casing-top 14 comprises a rigidly secured barrel, or cylindrical casing, 31 which depends

from the casing-top; a rotary locking-member 32 seated in the lower portion of the barrel 31; a tumbler, or key-guide, 33 confined in the barrel 31 above the member 32 and provided with a key-slot 34; a spring 35 encircling the locking-member 32 and serving to turn to and hold the locking-member 32 in locking engagement with the head 11 of the post A'; and a bearing-member, or plug 36 confined in the locking-member 32 and equipped with a spring 37 confined beneath the tumbler 33 and serving to dislodge or raise the shell and locking-member carried thereby with relation to the post A' when the rotary member 32 is released from engagement with the post.

The barrel 31 has an enlarged upper end 38 which is engaged and rigidly clamped to the lower surface of the casing-top by means of a flange 39 with which the annular plate 19 is provided. The tumbler, or rotary member, 33 has its upper end provided with a shoulder 40, and has a reduced portion 41 which extends into the central opening 42 with which the casing-top is provided. The shoulder 40 bears beneath the lower surface of the casing-top, as clearly shown in Fig. 5. The casing-top is surmounted by a name-plate 43 provided with a registering opening 44.

The fixed or stationary barrel 31 has its lower end provided with an opening 45 for the post and also has internal flanges, or shoulders, 46 and 47 adapted, respectively, as seating surfaces for the lower end of the member 32 and the lower surface of an external flange 48 with which the member 32 is equipped. The member 32 is also equipped at its upper end with a flange 49 provided with a key-slot 50 and a spring-engaging socket 51. The flange 48 of the member 32 is cut away or notched throughout substantially a quarter of its extent, as indicated at 52, and through the cut-away place extends the downturned end 53 of the spring 35, whose lower extremity enters a socket 54 with which the fixed barrel 31 is provided, as shown in Fig. 5. The other end 55 of the spring enters the notch 51, as shown in Fig. 5. The end walls 56 and 57 of the cut-away portion 52 of the flange 48 afford stops adapted to engage the downturned end 53 of the spring and limit the rotation of the member 52.

As shown in Figs. 5 and 10, the member 32 has a bore 58 which accommodates the plug, or bearing, 36 and the spring 37. At the lower end of the bore 58 are internal shoulders 59 which flank an elongated or substantially oval opening 60 adapted to allow the head 11 of the locking-member 9 of the post A' to enter the locking-member 32. This is permitted when the rotary locking-member 32 is turned or retracted against the action of its spring, and after the core is wholly

inserted in the shell, the member 32 is allowed to turn through the action of its spring to the locking position. It should be added that when the post A' enters the locking-member 32, the bearing member 36, which is normally seated on the internal shoulders 59 of the member 32, is raised against the pressure of the spring 37 to the position shown in Fig. 5.

10 The manner of use may be stated briefly. Assuming the savings bank to have its parts completely assembled and the core or body properly entered in the shell, the parts will be locked together by the locking-members 9 and 32, the springs 35 of the member 32 serving normally to hold the parts in locking engagement. The coins are inserted through the coin-slots in the usual manner, retracting the slot-guards 21 as they enter, 20 the coins dropping into the coin-receptacles. When it is desired to open the savings bank, a key is inserted through the slot 34 of the tumbler 33 and, engaging the slot 50 of the member 32, may be rotated to turn the member 32 from the locking position shown in Fig. 11 to the non-locking position shown in Fig. 12, whereupon the spring 37 will operate to force or start the shell from the core or body. In other words, the spring 37 30 operates to expel the locking-member 9 from the rotary locking-member 32, and as the locking-member 9 is carried by the post A' which rises from the base 1 of the shell, it is obvious that the shell will be loosened 35 from the core.

The foregoing detailed description has been given for clearness of understanding only, and no undue limitation should be understood therefrom, but the appended claims

should be construed as broadly as permissible in view of the prior art.

What I regard as new and desire to secure by Letters Patent is—

1. In a savings bank, the combination of a casing comprising a top wall and a vertical wall, said vertical wall provided with coin-slots, a body in said casing provided with coin-receptacles corresponding with said coin-slots, a sheet metal spider secured to the casing-top and provided near its periphery with openings, removable guide-cylinders seated in said openings, springs within said guide-cylinders, and slot-guarding plungers movable in said cylinders, said cylinders and plungers being provided with means adapted to interlock with the periphery of the openings to hold them in operative position therein.

2. In a savings bank, the combination of a casing comprising a top and a vertical wall, said vertical wall provided in its upper portion with coin slots, a body in said casing provided with coin receptacles corresponding with said coin slots, means for locking said body and casing together, a spider secured to the casing top and provided near its periphery with openings and with relatively narrow slots extending outwardly from said openings to the periphery of the spider, guide-cylinders seated in said openings, springs within said guide-cylinders, and slot-guarding plungers movable in said cylinders and having grooves engaging the walls of said relatively narrow slots.

IVER T LARSEN.
